RAIL ANCHOR TIE PLATE

Herbert T. Jones, Harrisburg, Pa.

Application August 21, 1952, Serial No. 305,617

13 Claims. (Cl. 238—304)

This invention relates to rail anchor tie plates and aims generally to improve the same.

Particular objects of the invention are to provide an improved rail anchor and tie plate construction; to reduce or largely eliminate the loosening of rail spikes under the impact of moving rolling stock; to cushion and quiet the trackage; to reduce or largely eliminate rail creep; and to provide novel structures and combinations of parts contributing to the realization of such objects. Further objects and advantages of the invention will be apparent from the following description of illustrative embodiments thereof.

In the accompanying drawings of such illustrative embodiments

Fig. 1 is a plan view of a first embodiment.

Fig. 2 is a partial transverse central section therethrough with the left hand portion shown in elevation.

Fig. 3 is a disassembled detail of one form of rocker assembly or rail clip as employed in Figs. 1 and 2.

Fig. 4 is a partial transverse section of a second embodiment.

Fig. 5 is a partial transverse section of a third embodiment.

Fig. 6 is a partial plan view of such third embodiment.

Referring to Figs. 1 to 3, the tie plate A is of a relatively light weight novel construction and is provided with means for securing it to a tie B and with means for securing in it a rail C.

The plate A in the form shown comprises a relatively thin base 1, say of $\frac{3}{8}$ " thickness, having integral therewith spaced parallel longitudinal reinforcing and rail retaining walls 2. Such retaining walls may have a thickness of $\frac{3}{4}$ " and may stand about $\frac{3}{4}$ " high at their retaining portions 2a. Integral with the retaining walls 2 are rocker bars 2b preferably having rounded under sides as shown (Fig. 2) and having a cross section of about 1" by $\frac{3}{4}$ ". These rocker bars 2b extend upwardly like bails or handles from the longitudinal reinforcing walls 2 and define rocker spaces in the form of passages or open slots thereunder of a height to extend sufficiently above the top surface of a rail flange C' to accommodate a rocker plate rail clip as hereinafter described.

Also integral with the base 1 and walls 2, the tie plate A comprises paired transverse reinforcing and rocker-retaining buttress walls 3 and further longitudinal reinforcing and retaining walls 4. The buttress walls 3 as shown may be relatively light, say of $\frac{3}{8}$ " thickness, and may have a height a little greater than that of the retaining walls 2, say a height of about 1", and the rocker retainer walls 4 may have a thickness of about $\frac{3}{8}$ " and a height of about $\frac{1}{2}$ ".

As is best shown in Fig. 1 the spaces between the walls 3 are preferably a little wider than the open slots or passages underlying the rocker bars 2b and the walls 2, 3 and 4 thus define between them rocker positioning housings or sockets bottomed by the base 1 of the tie plate and opening above the rail flange C' through the passages underlying the rocker bars 2b. In the form shown the bottom surfaces of these passages are spaced above the base 1 so that the reinforcing and retaining wall 2 extends continuously from end to end of the tie plate under the passages. In the form shown a single rocker bar 2b is provided at each side of the rail centrally of the length of the tie plate, but the invention is not limited to this form

2

and a plurality of separate rail clips or rockers may be used in a single tie plate at each side of the rail if desired.

The ends 2c and 3c of walls 2 and 3 are preferably fared down to meet the base 1, say at angles of 45° as best shown at 3c Fig. 2, and in similar manner the ends 2b of the rocker bar portions 2b are fared down, herein at 45°, to merge with the top surfaces of the wall portions 2a.

For lightness combined with adequate surface for the support of the rail and anti-creeping means therefor when used, the rail seat portion of the tie plate, comprising the walls 2 and the base between them, is extended somewhat beyond the portions of the base lateral thereof, the longitudinal extent of which need be only sufficient to accommodate the means at 5 for securing the tie plate A to the ties B.

The securing means at 5 may be of any conventional form and may vary depending on whether wooden or concrete or other forms of tie B are used and whether 20 the installation is made on land or on bridge or trestle structures. Hence the invention is not limited to any particular form of tie plate securing means at 5 where the tie plate is herein shown as provided with bolt or spike receiving apertures marginally reinforced by a 25 thickening of the base 1. The base 1 and wall and rocker bar elements 2, 2b, 3 and 4 may be cast integrally of suitable metal, in which case corners and wall junctions are appropriately filleted, or when desired the structure may be forged or fabricated in any other appropriate way.

The rail C in the form shown is typical of any standard rail as, say, a rail having a base flange of $5\frac{1}{2}$ " overall width.

As shown in Figs. 1 and 2 the rail base C' rests on the tie plate base 1 between the retaining walls 2, and a 35 rubber or like pad or cushion 6 may be interposed between the rail base C' and the tie plate base 1.

The means for retaining the rail in the tie plate comprises a rocker plate 7 extending under the rock bar 2b and having its inner end bearing on the flange of the rail C', there being associated with its outer ends jackscrew means for raising such outer end and fulcruming the plate on the under side of rocker bar 2b thereby to clamp the rail flange firmly in the tie plate. In the form shown the portion of the rocker plate 7 that extends through the passage into overlying relation with the rail flange is narrower than that portion of plate 7 that lies between walls 3. Shoulders are thus provided by which the plate is automatically correctly positioned, when inserted in the vent, in proper relation to provide for operation of the jack screw means.

The jack screw means in the form of Figs. 1 to 3 has threaded engagement with the outer wide end of the rocker plate which is thickened or reinforced as shown at 7a, Figs. 1 and 2 for the threaded engagement with the 55 jack screw 8. The lower end of the jack screw bears directly or indirectly on the base 1 of the tie plate A, and in the form shown has a reduced cylindrical section 8a that enters a centering aperture in a bearing plate 9 that is employed for spreading the load applied to lift the outer end of the rocker plate 7. The rocker plate 7 may be formed of steel plate or forging and may itself be slightly flexible to constitute or assist in the provision of a resilient means for clamping the rail flange in position.

To aid in such resilient clamping further means may be provided either singly or in combination, three such means being illustrated in the forms of Figs. 1 to 3. One of these means comprises a resilient rubber bearing cushion 10 interposed between the bearing plate 9 and the base of the tie plate A, the bearing plate 9 and resilient element 10 being positioned by the walls 2, 3 and 4, and aiding the walls 3 in positioning rocker plate 7. The second comprises a rubber or like resilient pad 11 vul-

canized or otherwise bonded to the under side of the rail flange clamping end of rocker plate 7 and aiding in maintaining a firm resilient engagement between plate 7 and the rail flange. The third comprises the rubber or like resilient pad 6 interposed between the rail base and the tie plate. Any and all of the rubber elements thus exemplified in the form of Figs. 1 to 3 may be employed or omitted, but when the elements 6, 7 and 10 are employed together an arrangement is provided that is especially effective in preventing creep of the rail and in avoiding permanent deformation of the plate 7 under the wave-like motion imparted to the rail by the passage of rolling stock thereover, and that affords a completely rubber mounting of the rail in the tie plate.

In assembling the arrangement of Figs. 1 to 3 the tie plate A, to which the pad 6 may be vulcanized or otherwise bonded, is placed in position, the rail is seated therein, the elements 9 and 10, if used, are dropped into the socket defined by walls 2, 3 and 4, rocker 7 is inserted through the vent until its shoulders engage wall 2, and the jack screw 8 is tightened until the desired clamping pressure is obtained. Since the jack screw means, consisting of the resilient members 10 and jack screws 8 is interposed between the opposed surfaces of the base and the outer ends of the rocker members 7, it serves to resiliently elevate and support the outer ends of the rocker plates 7. Any suitable means may be provided the jack screw 8, exemplified by kerfed heads herein. Equivalent means might constitute "Allen" or "Phillips" headed screws (i. e. screws having reentrant hexagonal sockets and tapered cruciform sockets rather than kerfs in their heads), for example.

When the resilient means 10 and 11 are provided, the vibrations imparted to the jack screw 8 by the wave motion of the rail are damped thus assisting in preventing loosening of the jack screw 8 in the installation. The arrangement shown also assists in the inspection and maintenance of the trackage as a simple touch by an inspector will disclose the loosening of any clamp and it is then a simple matter to restore its clamping action by further tightening of its jack screw 8. The resiliency afforded by the assembly allows a certain degree of wave motion of the rail and partially absorbs or damps the stresses resulting therefrom thereby reducing the tendency of the tie plate A to lift and exert undue pulling stresses on the means by which it is secured to the tie B. In this way loosening of such securing means is reduced or largely eliminated.

In the form of Fig. 4 the construction is similar to that shown in Figs. 1 through 3 and the corresponding parts are indicated by like reference numerals distinguished by "priming." This form differs from that shown in Figs. 1 to 3, however, in several respects. The resilient bearing means 10 in this instance is in the form of a helical metal spring 10' rather than a rubber pad, and the bearing plate 9' is centrally provided on its under side with a positioning boss entering the helical spring for centering it within the rocker socket. In addition in Fig. 4 the rubber pad 6' in accordance with my prior application Ser. No. 12,971, is vacuum bonded to the rail base C' and to the tie plate by the vacuum grip perforations 6a' therein. As further illustrated in Fig. 4 the screw jack 8' may be provided with a lock nut 8b' by which it can be secured against accidental backing off. This figure also illustrates in phantom at 7b' that the inner end of rocker 7 may be upwardly canted relative to the outer end to accommodate thicker rail flanges C', thicker bearing cushions 11', or thicker anti-creeping elements 6', and to increase the area of contact of the rocker or rocker cushion 11' with the rail flange. Finally in this embodiment a further silencing cushion 12' is inserted between the tie plate A and the underlying tie or other substructure B. It will be appreciated that each of the added features of this embodiment may be used separately or in combination in a structure otherwise similar to that of Figs. 1 to 3.

In the forms of Figs. 5 and 6 the structure again is

generally similar to that of Figs. 1 to 3 differing therefrom only in two respects. The first of these differences is that pad 6" in accordance with my above mentioned prior patent application is vacuum bonded to the under side of the rail base C' as by sockets 6a" and vulcanized or otherwise bonded to the tie plate A. The second resides in a reversal of the jack screw arrangement in which the jack screw 8" is threaded through a bearing plate 9" underlying the outer end of the rocker plate 7" and engages against the bottom of the jack screw socket in the tie plate A, the resilient means 10", shown as a helical spring centered on the bearing plate 9" being interposed between the bearing plate 9" and the rocker plate 7". In this form the outer portion of the rocker plate 7" and the resilient means 10" (that may be in the form of a rubber pad) are centrally apertured for the free passage of the jack screw 8" therethrough, lateral abutment of the parts serving to prevent slippage of the rocker plate 7" relative to the resilient means 10", though a spring-entering boss like that on plate 9" may be employed for this purpose. With this arrangement advance of the jack screw 8" lifts the bearing plate 9" against the resilient means which in turn lifts the outer end of the rocker 7" thereby rocking the same into firm engagement with the rail flange.

The tie plate of the present invention has an advantageous ratio of strength to weight; makes effective use of the materials employed, in an economical manner; is easily and quickly placed, adjusted and maintained; prolongs the life of the trackage and ties by its stress absorbing or damping capacity; and is particularly adapted for reducing rail creep, as will be apparent to those skilled in the art. Where the term "rubber" is employed herein, it is to be understood that synthetic as well as natural rubbery materials are contemplated.

While there have been described herein what are at present considered preferred embodiments of the invention, it will be obvious to those skilled in the art that minor modifications and changes may be made therein without departing from the essence of the invention. It is therefore to be understood that the exemplary embodiments are illustrative and not restrictive of the invention, the scope of which is defined in the appended claims, and that all modifications that come within the meaning and range of equivalency of the claims are intended to be included therein.

I claim:

1. A rail anchor tie plate comprising a base, spaced parallel rail retaining walls upstanding therefrom to receive a rail base therebetween, each of said retaining walls comprising an upstanding rocker-bar forming portion and having an open slot therethrough below said rocker-bar portion, rocker plates for extending one through each of said open slots with their inner ends in overlying relation to a rail base seated between said retaining walls and with their outer ends outside said walls, and adjustable jacking means for elevating the outer ends of each of said rocker plates.
2. A rail anchor tie plate comprising a base, spaced parallel rail retaining walls upstanding therefrom to receive a rail base therebetween, each of said retaining walls comprising an upstanding rocker-bar forming portion and having an open slot therethrough below said rocker-bar portion, rocker plates for extending through said open slots with their inner ends in overlying relation to a rail base seated between said retaining walls and with their outer ends outside said walls, said outer ends and said base presenting opposed surfaces, and adjustable means for resiliently elevating the outer ends of said rocker plates comprising resilient members and jack screw means for compressing said resilient members, said members and screw means being interposed between said opposed surfaces.
3. A rail anchor tie plate comprising a base, spaced parallel rail retaining walls upstanding therefrom to re-

ceive a rail base therebetween, each of said retaining walls comprising an upstanding rocker-bar forming portion and having an open slot therethrough below said rocker-bar portion, rocker plates for extending through said open slots with their inner ends in overlying relation to a rail base seated between said retaining walls and with their outer ends outside said walls, said outer ends and said base presenting opposed surfaces, said base having upstanding walls defining sockets for guiding said outer ends, a rubber bearing pad in each of said sockets, a bearing plate on each of said rubber pads, a jack screw threaded through each of said outer ends, and means for centering said jack screws on said bearing plates.

4. A rail anchor tie plate comprising a base, spaced parallel rail retaining walls upstanding therefrom to receive a rail base therebetween, each of said retaining walls comprising an upstanding rocker-bar forming portion and having an open slot therethrough below said rocker-bar portion, rocker plates for extending through said open slots with their inner ends in overlying relation to a rail base seated between said retaining walls and with their outer ends outside said walls, said outer ends and said base presenting opposed surfaces, said base having upstanding walls defining sockets for guiding said outer ends, a rubber bearing pad in each of said sockets, a bearing plate on each of said rubber pads, a jack screw threaded through each of said outer ends, and means for centering said jack screws on said bearing plates, said centering means comprising shoulders on said rocker plates abutting said retaining walls to center the jack screws relative to the bearing plates.

5. A rail anchor tie plate comprising a base, spaced parallel rail retaining walls upstanding therefrom to receive a rail base therebetween, each of said retaining walls comprising an upstanding rocker-bar forming portion and having an open slot therethrough below said rocker-bar portion, rocker plates for extending through said open slots with their inner ends in overlying relation to a rail base seated between said retaining walls and with their outer ends outside said walls, said outer ends and said base presenting opposed surfaces, said base having upstanding walls defining sockets for guiding said outer ends, a rubber bearing pad in each of said sockets, a bearing plate on each of said rubber pads, a jack screw threaded through each of said outer ends, and means for centering said jack screws on said bearing plates, said centering means comprising shoulders on said rocker plates abutting said retaining walls to center the jack screws relative to the bearing plates, and axial extensions on said jack screw entering centering apertures in said bearing plates.

6. A rail anchor tie plate comprising a base, spaced parallel rail retaining walls upstanding therefrom to receive a rail base therebetween, each of said retaining walls comprising an upstanding rocker-bar forming portion and having an open slot therethrough below said rocker-bar portion, rocker plates for extending through said open slots with their inner ends in overlying relation to a rail base seated between said retaining walls and with their outer ends outside said walls, adjustable means for elevating the outer ends of said rocker plates, rubber rail flange clamping pads carried by the under sides of the inner ends of said rocker plates, and a rubber pad mounted on said base and extending between said rail retaining walls for cooperating with said rail flange clamping pads to afford an all-rubber securement of the rail flange.

7. A rail anchor tie plate comprising, in combination, a base having upstanding rail retaining walls thereon, paired buttress walls extending laterally from said retaining walls, and bridge walls extending between said buttress walls in spaced relation to said rail retaining walls, said rail retaining walls comprising rocker bars extending thereabove between the paired buttress walls

and having openings under said rocker bars, rocker plates for extending through said openings with their inner ends in overlying relation to a rail base seated between said rail retaining walls and with their outer ends positioned between said paired buttress walls, and jack screw means positioned at least in part by said paired buttress walls for elevating the outer ends of said rocker plates to clamp said rail base between said inner ends and said base.

10. A combination according to claim 7, said jack screw means comprising interposed resilient elements and operating to resiliently elevate and support said outer ends.

15. A combination according to claim 8, in which the resilient elements interposed in the jack screw means consist of rubber pads supported on the base, and in which the jack screw means comprise jack screws threaded through said outer ends and engaging bearing plates supported by said rubber pads.

20. A combination according to claim 8, in which the resilient elements interposed in the jack screw means consist of helical springs and in which the jack screw means comprise jack screws threaded through said bearing plates and engaging said base, said bearing plates underlying said outer ends and said helical springs being interposed between said bearing plates and said outer ends.

25. 11. A rail anchor tie-plate sub-combination comprising a flat base, upstanding rail retaining walls thereon, pairs of spaced apart buttress walls extending laterally from each of said rail retaining walls, and bridge walls extending between the buttress walls of each pair in spaced relation to said rail retaining walls, said rail-retaining-, paired buttress-, and bridge-walls defining at each side of the tie plate a wall surrounded rail clip socket, said rail retaining walls comprising rocker bars extending thereabove between the paired buttress walls and said rail retaining walls having openings under said rocker bars for the extension of rocker plates therethrough.

30. 12. A rail anchor tie plate sub-combination comprising a flat base with upstanding rail retaining walls thereon, said rail retaining walls comprising rocker bars extending thereabove and having openings under said rocker bars for the extension of rocker plates therethrough, and said base having pairs of spaced apart transverse rocker retaining buttress walls laterally guiding said rocker plates and defining rail clip rocker sockets positioned outwardly of and in alignment with said rocker bars.

35. 13. A rail anchor tie plate sub-combination comprising a flat base with upstanding rail retaining walls thereon, said rail retaining walls comprising rocker bars extending thereabove parallel to their length and having openings under said rocker bars for the extension of rail clip rocker plates therethrough, and said base having pairs of spaced apart transverse rocker retaining buttress walls laterally guiding said rocker plates and longitudinal retaining walls spaced outwardly from said rail retaining walls, said longitudinal and transverse walls defining rail clip rocker sockets positioned outwardly of and in alignment with said rocker bars.
